UNITED STATES PATENT OFFICE.

PAUL PATRICK EMIL RICHARDS, OF OMAHA, NEBRASKA, ASSIGNOR OF ONE-HALF TO ARTHUR J. CARTER, OF OMAHA, NEBRASKA.

TRAIN-STOPPING MECHANISM.

Application filed November 6, 1918, Serial No. 261,350. Renewed March 31, 1922. Serial No. 548,525.

To all whom it may concern:

Be it known that I, PAUL P. E. RICHARDS, a citizen of the United States, residing at Omaha, in the county of Douglas and State 5 of Nebraska, have invented certain new and useful Improvements in Train-Stopping Mechanism, of which the following is a specification.

This invention relates to improvements in 10 train stopping mechanism and its prime object is to prevent railroad wrecks that are ordinarily caused by the train crew failing to observe danger signals. A further object is to provide a device to prevent wrecks 15 that is of simple construction and efficient in operation. With the foregoing and other objects in view the invention consists in the combination and arrangement of parts to be hereinafter fully described, pointed out in 20 the appended claims and illustrated in the accompanying drawings which form a part of this specification and in which—

Fig. 1 is a side view of the ordinary 25 semaphore with operating connections therefor.

Fig. 2 is a fragmentary view of a locomotive cab illustrating the application of my mechanism.

Fig. 3 is a view of a modified form of 30 semaphore connection illustrating its application to the railway track.

Fig. 4 is a top plan view of Fig. 3.

Fig. 5 is an enlarged fragmentary sectional view of Fig. 2.

Fig. 6 is a top plan view of Fig. 5.

Fig. 7 is a fragmentary view in elevation of the mechanism shown in Fig. 1.

Fig. 8 is a top plan view of Fig. 7.

Like reference characters denote corresponding parts throughout the several views.

The reference numeral 1 denotes the usual semaphore post the arm 2 of which is connected by pitman 3 to the bell-crank-lever 4, fulcrumed to the semaphore post 1, which is connected to the cross rod 5 which is operated by the hand lever 6 within the tower house 7. To the cross rod 5 beneath one rail 8 I secure one end of another bell-crank-lever 9 fulcrumed to a rail tie 10, the opposite end of said bell-crank-lever being slotted longitudinally to receive the pin 11 that connects it to the trip 12 which is provided with the convex head 13, said trip 55 extending through the guide plates 14 which are secured to the tie and braced against the web of the rail 8, the head 13 of said trip being spaced away from the rail tread to form clearance for the wheel flange. In Figs. 3 and 4 a modified construction is 60 shown. A plate 15 is recessed longitudinally to form a seat for a sliding plate 16 which is formed with a slot 17 to receive a screw 18 by which it is secured to the said plate 15 and to the rail tie 10. The said sliding plate 16 is formed with upstanding ears 19 to which a convexo-concave plate 20 is secured by a bolt 21^a; a bolt 21 connects one end of the plate 20 to the cross rod 5. It will be noted that the plates 16 and 20 are 70 slidable upon the plate 15 toward or away from the rail 8, the plate 15 being recessed adjacent the rail to form a passageway for the wheel flange.

Within the cab 21^b of the engine upon the 75 air brake line 22 I arrange a cylinder 23 formed with sectional air passages 24, 25 into which passages the main air line 22 is fitted as shown; the sections 24, 25 being spaced apart to permit insertion of the piston rod 26 which is formed with an air passage 27 which is moved into or out of register with the sectional air passages 24, 25 by movement of the said piston, said piston extending entirely through the cylinder and 80 being formed at its upper end with a rack for engagement with a pawl 29 fulcrumed upon the cylinder. The said piston 26 extends through the floor of the cab and through a sleeve 30 depending from the 90 cab and at its lower end carries a convex head 31, or it may carry a cam block 32 for engagement with the sliding elements shown in Figs. 3 and 4. When the semaphore is set for danger as shown in full lines in Fig. 95 1 the trip 12 is raised, or in Figs. 3 and 4 the sliding elements are positioned the maximum distance from the rail 8. As the engine passes the semaphore in danger position the head 31 engages with the trip head, 100 or the cam block engaging the plate 20 will effect the same result, which raises the piston 3, the head 31 or block 32 limiting the upward movement of said piston by contact with the lower end of the sleeve 30, and at 105 the time of such contact with said sleeve the port 27 in piston 26 will register with the air passages 24, 25 in the cylinder thus permitting the air in line 22 to automatically set the train brakes and stop the train. The 110

pawl 29, it will be noted, will retain the piston 26 in raised position thus insuring that the brakes will remain set until the train comes to a full stop and until the engineer 5 from his cab disengages the pawl and rack to permit the piston 26 to assume normal position.

What is claimed is:—

1. In train stopping mechanism, signal 10 control mechanism, a cylinder carried upon the train air pipe, said cylinder being formed with aligned air passages spaced away from each other and communicating with the train air pipe, a piston extending 15 through said cylinder between its aligned air passages and formed with an air passage normally out of register with said cylinder air passages, means carried by said piston for contact with said signal control 20 mechanism whereby said piston is raised to cause its air passage to register with the aligned cylinder air passages, and means fulcrumed to said cylinder for releasable engagement with the upper end of said piston 25 to retain the same in raised position.

2. In train stopping mechanism, a trip, a cylinder carried by the train air pipe, said cylinder being formed with aligned air 30 passages spaced away from each other and communicating with the train air pipe, a toothed piston extending through said cylinder between its aligned air passages and formed with an air passage normally out

of register with said cylinder air passages, a head terminally carried by said piston for 35 contact with said trip whereby said piston may be raised to cause its air passage to register with the aligned cylinder air passages, and a pawl fulcrumed to said cylinder for engagement with the toothed portion 40 of said piston.

3. In train stopping mechanism, signal 45 control mechanism, said mechanism including a sliding block, a cylinder carried by the train air pipe, said cylinder being formed with aligned air passages spaced away from each other and communicating with the train air pipe, a piston extending through 50 said cylinder between its aligned air passages and formed with an air passage normally out of register with said cylinder air 55 passages, a cam block carried by said piston for contact with said sliding block whereby said piston is raised to cause its air passages to register with the aligned cylinder air passages, and means fulcrumed to said cylinder for releasable engagement with the upper end of said piston to retain the same in raised position.

In testimony that I claim the foregoing as 60 my own I have hereto affixed my signature in the presence of two subscribing witnesses.

PAUL PATRICK EMIL RICHARDS.
